(57) **CLAIM**

The ornamental design for a pet kennel, as shown and described.

DESCRIPTION

FIG. 1 is a perspective view of a pet kennel showing our new design;

FIG. 2 is a front elevational view thereof;

FIG. 3 is a rear elevational view thereof;

FIG. 4 is a right side elevational view thereof, the left side elevational view being a mirror image thereof;

FIG. 5 is a top plan view thereof;

FIG. 6 is a bottom plan view thereof;

FIG. 7 is a front elevational view of a second embodiment of FIG. 1;

FIG. 8 is a rear elevational view of FIG. 7;

FIG. 9 is a right side elevational view of FIG. 7, the left side being a mirror image; and,

FIG. 10 is a top plan view of FIG. 7, the bottom being identical to FIG. 6.
